DISPENSING MACHINE

Lawrence M. Persons, St. Louis County, Mo.

Application December 3, 1938, Serial No. 243,693

10 Claims. (Cl. 312—97)

The present invention relates generally to dispensing devices, and more particularly to dispensing machines for cigarettes, candy bars, and the like, employing a plurality of bucket chains as carriers for the products dispensed.

An object of the present invention is to provide a novel dispensing machine which includes rotatable carriers for dispensed products.

Another object of the present invention is to provide a novel dispensing machine which includes a plurality of bucket chains as the carriers for the product dispensed.

Another object is to provide a novel dispensing machine employing bucket chains as carriers and having a novel release and locking mechanism adapted to dispense one item from a selected one of said carriers.

Another object is to provide a novel dispensing machine having chain bucket carriers for the products, which includes a cooperative coin-handling mechanism.

Another object is to provide a novel dispensing machine having chain bucket carriers which includes a cooperating governor adapted to regulate the speed of the carriers in their dispensing movements.

Another object is to provide novel means for preventing unwarranted back-up movement of the rotatable carriers.

Another object is to provide a novel dispensing machine which includes chain bucket carriers mounted about spaced axes of revolution and individually spring-actuated.

Another object is to provide a novel dispensing machine including a plurality of chain bucket carriers, each of which is operable from an initial relatively short movement of its operating device.

Another object is to provide a novel dispensing machine, substantially all the operating elements of which are pivotally mounted to insure easy operation from an initiating short movement of an operating device.

Another object is to provide a novel dispensing machine of large capacity through the use of continuous bucket chains as carriers.

Another object is to provide a novel dispensing machine which can be readily manufactured, which is adapted to function for a long period of time without failure due to the relative simplicity of the operating mechanism which is both easy and simple to operate, and which is substantially vermin-proof.

Other objects and advantages will be apparent from the following description, taken in conjunc-

tion with the accompanying drawings, in which:

Fig. 1 is a side elevation of a dispensing machine constructed in accordance with the teachings of the present invention;

5 Fig. 2 is a front elevation of the machine shown in Fig. 1;

Fig. 3 is a view of the other side of the machine shown in Fig. 1;

Fig. 4 is a section on the line 4—4 of Fig. 2;

10 Fig. 5 is an end elevation of the machine shown in Fig. 1 on an enlarged scale, the casing being in section, and a part of the casing being broken away for conservation of space;

Fig. 6 is a section on the line 6—6 of Fig. 2;

15 Fig. 7 is a section on the line 7—7 of Fig. 5;

Fig. 8 is a section on the line 8—8 of Fig. 7;

Fig. 9 is an end elevation of the other end of the machine from that shown in Fig. 5, the casing being in section, the lower part of the casing being broken away for preservation of space;

Fig. 10 is a section on the line 10—10 of Fig. 2;

Fig. 11 is a portion of Fig. 9 on a larger scale to illustrate more clearly details of the coin-handling mechanism;

20 Fig. 12 is a portion of Fig. 6 on an enlarged scale showing details of the carrier release and locking mechanism;

Fig. 13 is a section on the line 13—13 of Fig. 6;

25 Fig. 14 is a view of the coin-handling mechanism shown in Fig. 11 with the mechanism moved to a position to deposit coins in a receiving container;

Fig. 15 is a view of the coin-handling mechanism shown in Fig. 11 with the mechanism in coin-return position;

Fig. 16 is a section on the line 16—16 of Fig. 11;

Fig. 17 is a section on the line 17—17 of Fig. 11;

Fig. 18 is a perspective view of the carrier release and locking mechanism;

30 Fig. 19 is a perspective view of a portion of the coin-handling mechanism;

Fig. 20 is a perspective view of an element of the coin-handling mechanism;

Fig. 21 is a view of a blank from which an individual bucket is formed;

Fig. 22 is a perspective of one of the buckets forming a bucket chain carrier; and,

35 Fig. 23 is a perspective view of a novel locking means to prevent unwarranted back-up rotation of the carriers.

Referring to the drawings more particularly by reference numerals, 30 indicates generally a dispensing machine constructed in accordance with the concepts of the present invention. The machine 30 includes an outer cover or case 31 com-

prising an upper section 32, a lower section 33 which rests on a base 35, and a U-shaped strip 34 of channel cross-section between the upper section 32 and the lower section 33.

The strip 34 includes a plurality of apertures 42 (Figs. 2 and 12), in each of which is a push-button 43.

The upper section 32 includes a plurality of openings 44 (Fig. 2) for a purpose to be described, coin slots 45, and an elongated slot 46 beneath the openings 44 for inspecting the product being dispensed. A single coin slot may be employed, depending upon the coin selector used.

A support for the operating mechanism of the machine 30 and the case 31 comprises spaced heavy end plates 50 (Fig. 5) and 51 (Fig. 9) which are secured to the base 35 by bolts 52, or the like. A rear plate 54 is removably connected to the end plates 50 and 51 by screws 55 which engage flanges 56 and 57 of the end plates 50 and 51, respectively (Figs. 4 and 5). The end plates 50 and 51 are of a configuration to approximate the cross-section of the cover 31, as is apparent from Figs. 5 and 9. The lower section 33 of the cover 31 is removably secured to the flanges 56 and 57 of the plates 50 and 51 by the screws 55 (Fig. 10). The strip 34 is welded or otherwise secured to the plates 50 and 51. The upper section 32 is pivotably connected by hinges 58 to the rear plate 54.

A shaft 60 (Figs. 4 and 6) is supported by the plates 50 and 51 towards the upper ends thereof, being maintained in fixed relation by nuts 61. Double sprockets 62 are freely rotatable on the shaft 60, being maintained in predetermined positions thereon by suitable collars 63. Each sprocket 62 includes spaced sprocket wheels 64 and 65 connected in spaced relation by pins 66. The sprocket wheel 64 includes alternately outwardly turned ears or stops 67 (Figs. 4 and 12) and semi-circular notches 68. The stops 67 are preferably at right angles to the plane of the sprocket wheel 64 and angularly disposed relative to a radius, as shown in Fig. 12. The sprocket wheel 65 includes semi-circular notches 69 spaced similarly to the semi-circular notches 68 of the sprocket wheel 64. A heavy expandible spring 70 is associated with each sprocket 62, one end of which is secured to the shaft 60 by suitable means, such as a screw 71 while the other end is fixed to one of the pins 66 by a screw 72. Each spring 70 tends at all times to rotate its respective sprocket 62 in a counter-clockwise direction (Fig. 12).

A shaft 75 (Figs. 6 and 10) is journaled in the end plates 50 and 51 a predetermined distance below the shaft 60, being maintained in position by a collar 76 at one end and by a gear 77 fixed by a set screw 78 thereto at the other end. Double sprockets 79 are freely rotatable on the shaft 75, there being the same number of sprockets 79 as there are sprockets 62. Each sprocket 79 includes sprocket wheels 80 and 81 spaced and maintained in assembled relation by pins 82, each of the sprocket wheels 80 and 81 including spaced semi-circular notches 83 on the periphery thereof. A collar 84 and a gear 85 mounted on a hub 86, fixed to the shaft 75 by set screws 87, maintain each sprocket 79 in predetermined position on the shaft 75. Pawls 70 are pivoted to each sprocket wheel 80 in position for one-way locking engagement with the teeth of the gear 85.

A governor generally designated 88 (Figs. 4, 5, 7, and 8) is connected to the shaft 75 to limit

the speed of rotation thereof, being located between the end plate 50 and an end of the cover portion 31. The governor 88 includes the aforementioned gear 77 fixed to the shaft 75 by the set screw 78. A plate 81 is fixed to the end plate 50 by screws 82 which are surrounded by spacers 83. A shaft 84 is journaled in the plates 50 and 81 to which is fixed a gear 85 by a suitable associated collar 86 and set screw 87. A pinion 88 is fixed to the gear 85 concentric therewith, and engages the gear 77. A second shaft 89 is journaled in the plates 50 and 81 to one side of and above the shaft 84 to which is fixed a pinion 90. The pinion 90 engages the gear 85. Spring-arms 101 and 102 are fixed to the shaft 89 by a nut and bolt assemblage 103. The spring arms 101 and 102 are of the configuration clearly shown in Fig. 8, each having fixed to the free end thereof a weight 104 and a pad 105. The pads 105 engage the inner surface of an annular wall 106 of a cup 107 concentric with the shaft 89 and fixed to the plate 81 by screws 108 (Fig. 7). It is clear that the just-described mechanism retards the speed of rotation of the shaft 75.

A continuous bucket chain carrier 110 is associated with each pair of opposed sprockets 62 and 79. Each carrier 110 includes a plurality of buckets 111 (Figs. 6 and 22). Each bucket 111 has opposed sides 112 of the configuration shown, a bottom 113, an end 114, and an abbreviated top 115. Each side 112 includes an eyeleted aperture 116 and a post 117. The portion of each side 112 bearing the eyeleted aperture 116 is offset outwardly from that portion bearing the post 117. The top 115 is secured to the sides 112 by extensions 118 which engage suitable slots in the aforesaid sides 112. The buckets 111 are of integral construction, being formed from a blank of the configuration shown in Fig. 21. It is apparent that the posts 117 of one bucket fit into the eyeleted apertures 116 of an adjacent bucket to form the bucket chain. The offset portions of the sides 112 permit ready connection of the buckets 111 and permit free pivotal action necessary for the buckets to move around the sprockets 62 and 79 at each end of the carrier.

Each carrier 110 is disposed about opposed sprockets 62 and 79 with the posts 117 engaging the semi-circular notches 68 and 83, respectively (Fig. 6). One bucket 111 of each carrier 110 has a stop 120 for a purpose to be described. Guides 121 and 122 fixed to and between the end plates 50 and 51 prevent displacement of the carriers inwardly.

A guide shield 123 is disposed about the carriers 110 (Fig. 6), being connected by a flange 124 to the strip 34 (Fig. 12) and by a flange 125 to the rear plate 54. The guide shield 123 is extensive and abuts the end plates 50 and 51 (Fig. 10), whereby the carriers 110 and the products carried thereby are enclosed.

A release and locking mechanism 130 (Figs. 6, 12 and 18) is provided, whereby the carriers 110 may be actuated individually. A shaft 131 (Fig. 16) is journaled in the end plates 50 and 51 for rotation. A second shaft 132 is suspended from the shaft 131 by arms 133 rigid with the shaft 132 and fixed to the shaft 131 by a set screw 134. Adjacent each of the sprockets 62 are two bell crank levers 135 and 136 (Fig. 18) which are disposed in contiguous relation and both of which are connected by a lever 137 to the respective push-button 43 (Fig.

12), the lever 137 being pivotally connected to the arms 138 and 139 of the bell crank levers 135 and 136. The bell crank 135 includes a second arm 140 which terminates in a right-angular extension 142. The extension 142 is normally adapted to contact a stop 87 of the associated sprocket 62 (Fig. 6). The bell crank 136 includes a second arm 143 having an elongated arcuate flange 144 (Figs. 12 and 18) and a weight 145. The arcuate flange 144 is adapted to be contacted by the stop 87 preceding the stop 87 contacting the extension 142 upon release of the extension 142 from its contiguous stop 87 if the extension 142 is not allowed to drop back to normal position to prevent unnecessary rotation of the sprocket 62 and to insure successive contact of the extension 142 with the stops 87. An angle bracket 146 is fixed to each lever 137 for cooperation with the respective stop 120.

A locking device 148 of well-known construction is provided for preventing the operation of more than one carrier 110 at a time. The locking device 148 includes a plurality of slidable plate 149 (Fig. 13) which are disposed in end-to-end relation beneath the central portion of the guide 121, each including a pair of slots 150 engaging rivets 151. Each plate 149 is cut away at opposed corners to provide a V between contiguous plates 149. The total overall free space provided is just sufficient to permit the ends of the arms 138 and 139 of one pair of bell cranks 135 and 136 to be moved between two plates 149. Two push buttons 43, therefore, cannot be moved inwardly simultaneously.

A coin selector 160 (Fig. 11) of well-known construction is fixed by suitable means to the upper portion of the end plate 51. For present purposes, it is sufficient to mention a double coin chute 161 which communicates with the coin slots 45 in the upper section 32 of the case 31.

A coin-handling mechanism 155 is shown clearly in Figs. 9, 11, 13-17, 19, and 20. Referring to Fig. 19, the coin-handling mechanism 155 includes three contiguous plates 163 and three contiguous plates 164 maintained in predetermined spaced relation by pins 165. The plates 163 include aligned apertures 166 adjacent the upper edge thereof and aligned slots 167 towards the lower edge thereof. Each slot 167 includes a short narrow portion 168 and a wide portion 169 at the junction of which is a shoulder 170. The intermediate plate 163 is cut away to provide a coin slot 159 (Fig. 17), the sides of which are defined by the outer plates 163. The plates 164 include aligned slots 171 and 172 spaced vertically, the slots 172 being of greater length than the slots 171. Each of the slots 171 includes a narrow portion 173 and a wide portion 174, at the juncture of which is a shoulder 175. Each of the slots 172 includes a narrow portion 176 and a wide portion 177 at the juncture of which is a shoulder 178. The intermediate plate 164 is cut away to provide a coin slot 158 (Fig. 17), the sides of which are defined by the outer plates 164. The coin slots 158 and 159 are disposed to receive coins from the slots 161 forming part of the coin selector mechanism 160 (Fig. 11). Each of the slots 167, 171, and 172 is arcuate in cross-section, being a part of a respective circle, the centers of which coincide with the center of the apertures 166. A lever 180 is pivoted to a post 181 fixed to the plate 51 and includes at its free end an extension 182 disposed in the slots 171 (Figs. 11 and 19). A lever 183 is pivoted to a post 184 fixed to the plate 51 and includes an

extension 185 disposed within the slots 172. A lever 186 (Fig. 19) is likewise pivoted to the post 184 and includes an extension 187 (Fig. 16) disposed in the slots 167. The levers 180 and 186 are connected by a strip 188 for simultaneous movement.

Referring to Fig. 16 the aligned apertures 166 are disposed about a reduced extension 191 of the shaft 131. A nut 190 securely forces the plates 163 against the shoulder setting off the reduced extension 191.

A coin stop 192 (Figs. 16 and 20) including a main body portion 193 and an arcuate flange 194 is pivoted by means of an aperture 195 on the shaft 131 adjacent the outer plate 163. A link 196 is pivoted to the main body 193 of the coin stop 192 by a suitable rivet 197, or the like, at one end and is fixed to a button 199 (Figs. 14 and 15) similar to the buttons 43 at the other end. A spring 204 biases the link 196 and the coin stop 192 into the positions shown in Fig. 14. The button 199 is disposed to reciprocate in an aperture 200 in the strip 34. As is evident, the flange 194 is adapted to be disposed adjacent the lower edge of the coin-handling mechanism 155. The lower edge of the coin-handling mechanism 155 and the flange 194 are segments of concentric circles.

Beneath the coin-handling mechanism 155 are a coin return chute 201 and a coin-receiving box 202 (Fig. 9) which may be of any desired configuration. The coin return chute 201 opens through the lower section 33 of the casing 31 at 203.

An angle member 205 including sides 206 and 207 is pivotally supported at its ends by plates 50 and 51 (Figs. 4, 6, and 9), being disposed adjacent the upper edges of the sprockets 79. A flat member 208 is loosely connected to the side 206 adjacent each sprocket 79 by a reduced extension 209 (Fig. 23) through which extends a cotter pin 210, or the like. The free end of each member 208 normally rests on one of the sprocket wheels of the respective sprockets 79. A wire 211 is connected to the side 207 and to a suitable point of the underside of the upper section 32.

It is apparent that the structural details of the just-described dispensing machine 30 may be varied within the limits of the invention. The particular configuration of the case and the particular configuration of the working parts may vary from those shown in the drawings, as is palpable. It is fully contemplated that more or less than four carrier units may be employed in a completed dispensing machine. Further, it is fully appreciated that the carriers may be of sufficient length to require the disposition of the lower shaft 75 and its associated mechanisms just above the base 35, thereby lending maximum capacity to the machine.

With some machines 30 a change-making mechanism is employed, being required by statute. Where such mechanisms are used the coin return chute 201 and the coin-receiving box 202 are located differently from the present disclosure in order to receive their proper coins from both the coin-handling mechanism 155 and such change-making mechanism.

Operation

The present dispensing machine 30 is particularly adapted for the vending of cigarettes, although other products, such as candy bars, and the like, may be sold or distributed by it. For

purposes of illustration, it will be assumed that cigarettes, each package with a paper of matches, are being dispensed by the machine 30.

With the machine 30 empty, the carriers 110 will be disposed with the stops 120 (Fig. 6) adjacent the angle brackets 146. It is obvious that, with the stops 120 adjacent the angle brackets 146, the push buttons 43 cannot be moved inwardly, thereby indicating that the carriers 110, or a particular carrier 110, are empty. Let it be assumed that all of the carriers 110 are empty, although for the purpose of this discussion of operation only one carrier 110 will be considered, inasmuch as the several carriers 110 are identical both in construction and in operation.

The upper section 32 of the cover 31 is thrown backwardly about the hinges 59, which pivots members 208 into inoperative positions and which reveals the upper elements of the internal mechanism. A pack of cigarettes with a package of matches on top is disposed in each bucket 111 of the carrier 110 exposed to view. The carrier 110 is then rotated manually in a clockwise direction (Fig. 6) moving the loaded buckets 111 downwardly and exposing additional empty buckets 111. The empty buckets 111 now exposed are loaded and the foregoing action repeated until all of the buckets 111 are loaded.

The manual movement of the carrier 110 clockwise winds the heavy actuating spring 70, providing power for subsequently automatically moving the carrier 110 counterclockwise in the dispensing of the cigarettes. The carrier 110 can be manually moved clockwise without throwing into action the governor 90, since the lower sprocket 79 is freely rotatable on the shaft 75, and the pawls 88 pivoted thereto ride over the gear 85 fixed to the shaft 75 in this clockwise movement of the sprocket 79 (Fig. 6). The guide shield 123 insures that the buckets 111 retain the cigarettes and matches deposited therein (Fig. 6).

After the carrier 110 is fully loaded, the upper section 32 of the cover 31 is lowered against the strip 34 and locked in position by suitable locking mechanism. The carrier 110 is then ready to dispense the cigarettes and matches contained in the buckets 111.

Three nickels or a dime and a nickel are deposited in the respective slots 45 (Fig. 2). The coins move through the chutes 161 (Fig. 11) of the coin selector 160 and into the proper coin slots 158 and 159, being stopped at the bottom of the aforesaid coin slots 158 and 159 by the flange 194 of the coin stop 182. Where three nickels 205 are employed, the nickels will assume the positions shown in Fig. 11, the bottom nickel 205 extending into the defined area of the slots 172 and the top nickel extending into the defined area of the slots 171.

The button 43 is pushed inwardly to the position shown in Fig. 12. Movement of the button 43 inwardly pivots the bell cranks 135 and 136 clockwise (Fig. 12), thereby releasing the extension 142 from engagement with the stop 67 thereagainst. The pivotal movement of the bell cranks 135 and 136 moves the shaft 132 in a clockwise direction, thereby pivoting the shaft 131, which is connected with the coin-handling mechanism 155 (Fig. 16). Inasmuch as the three nickels 205 are in the respective positions shown in Fig. 11, the coin-handling mechanism 155 can be pivoted counterclockwise (Fig. 11), whereupon the extensions 182 and 185 of the levers 180 and 183, respectively, ride over the portions of the

nickels 205 within the slots 171 and 172, respectively, as a lift into the narrow portions 173 and 176, respectively, from the wide portions 174 and 177, respectively. It is, of course, clear that were the nickels 205 not in the coin slot 158 then the extensions 182 and 185 would strike the shoulders 175 and 178, respectively, blocking further movement of the dispensing mechanism.

As the engaged stop 67 is released from the extension 142 of the bell crank 136, the spring 70 fixed to the shaft 60 rotates the sprocket 62 counterclockwise (Fig. 12). Should the button 43 be maintained in the position shown in Fig. 12, the next stop 67 following the released stop 67 will engage the arcuate flange 144 of the bell crank 136. However, as the button 43 is released, the weight 145 forces the bell cranks 135 and 136 back into the positions shown in Fig. 6, whereupon the sprocket 62 continues in its rotation through the force of the spring 70 until the aforesaid next succeeding stop 67 engages the extension 142 of the bell crank 135. During the rotation of the sprocket 62, the carrier 110 is moved just sufficiently to raise the next full bucket 111 from stamp inspection position into dispensing position opposite the respective opening 44 (Fig. 2).

Considering Fig. 6, the bucket 111, during the aforesaid movement of the sprocket 62, moves from stamp inspection position, in which the upper and lower defining walls are in substantially parallel relationship, the upper defining wall actually being the bottom of the bucket 111, into the position of bucket 111², in which position 30 the upper and lower defining walls are in diverging relationship, the upper defining wall, of course, being the bottom of the next higher bucket 111. The spreading apart of the defining walls of the buckets 111, as they move around the half circle with the shaft 60 as a center, permits the cigarettes and matches within the particular dispensing bucket 111 to be readily removed therefrom, since the aforesaid spread adds a sufficient amount of space for the fingers of a person removing cigarettes and matches from the bucket. The spreading of the buckets 111 as they move around the contacted semi-circle of the sprocket 62 is, of course, occasioned by the fact that the circle of the outer edges of the buckets 50 is of greater circumference than the circle defined by the posts 117.

The governor 90 (Figs. 5-8) functions to soften the force of the springs 70. The springs 70 of necessity must be strong in order to rotate the carriers 110, and a particular spring 70 would rotate its carrier 110 at relatively high speed were the governor 90 not attached to the shaft 75. As a carrier 110 is moved by its spring 70, the sprocket 79 is rotated, carrying with it the pivoted pawls 88 which, in the counterclockwise movement of the sprocket 79 (Fig. 6) occasioned by the spring 70, engages the teeth of the gear 85 which, being fixed to the shaft 75, rotates the shaft 75 to throw the governor 90 into action to slow down the otherwise rapid rotation of the carrier 110 and the associated mechanism. The particular functioning of the elements of the governor 90 need not be detailed here, since the governor 90 is of well-known construction and its operation is obvious from the foregoing description and the accompanying drawings. Were the governor 90 not used, the buttons 43 would be kicked back through the force of the associated springs 70, an undesirable reaction. The

employment of the governor 30 results in a smooth return of the buttons 43.

As the bell cranks 135 and 136 are pivoted by movement of the button 43 inwardly, the lower ends thereof are moved between two plates 149 (Figs. 12 and 13). With the ends of the bell cranks 135 and 136 between two plates 149, a second carrier 110 cannot be operated, for the remaining plates are contiguous and block any separation attempt inasmuch as the overall free space is occupied by the ends of the bell cranks 135 and 136.

It is, of course, apparent that the levers 188 and 186 are simultaneously raised so that it is but necessary to positively raise either the extension 182 of the former or the extension 187 of the latter to permit operation of the machine 30. This permits a package of cigarettes to be secured either through the deposit of a dime and a nickel or three nickels.

In a full stroke of any push button 43 to purchase a particular package of cigarettes, the coin-handling mechanism is moved from the position shown in Fig. 11 to the position shown in Fig. 14. As the coin-handling mechanism 155 assumes the relationship shown in Fig. 14, the coins in the coin slots 158 and 159 drop by gravity into the coin-receiving container 202, for the coin slots 158 and 159 are moved beyond the effective retaining surface of the flange 194. The machine 30 is constructed to permit the coin-handling mechanism to hesitate sufficiently long in the position shown in Fig. 14 to deposit the purchasing coins in the coin-receiving container 202.

Should the potential purchaser change his mind relative to the purchase of a particular brand of cigarettes after depositing his coins but before pushing a selected button 43, he may recover his coins by moving the push button 199 (Fig. 15) inwardly. Movement of the push button 199 moves the coin stop 192 from the position shown in Fig. 11 to the position shown in Fig. 15. In the aforesaid latter position of the coin stop 192, coins in the coin slots 158 and 159 drop into the coin return chute 201. The potential purchaser can then readily recover the coins by extending his hand through the opening 203.

In cases where the coin selector 160 refuses to pass a coin into either the coin slot 158 or slot 159 of the coin-handling mechanism 155, the rejected coin can be recovered by the individual inserting it into the machine 30 by moving the button 199 inwardly into the position shown in Fig. 15. The inward movement of the button 199 actuates an element of the coin selector 160 to release the rejected coin or coins into the slots 158 or 159 with the coin stop 192 in the position of Fig. 15. The rejected coin or coins will pass through the slots 158 and 159 into the coin return chute 201.

When the last loaded bucket 111 of a particular carrier 110 reaches the respective opening 44, the stop 120 (Fig. 6) will be opposite the angle bracket 146. Further attempts to purchase cigarettes from that carrier 110 through movement of the button 43 inwardly will result in contact of the angle bracket 146 against the stop 120, which will block further operation of that particular carrier 110. It is contemplated that some designation be inscribed within the last loaded bucket 111 to indicate, when empty, that the cigarettes are exhausted in that carrier 110. It is also contemplated that each bucket 111 of

75 a carrier 110 be numbered to indicate the number of packages of cigarettes remaining in the carrier 110.

The angle member 205 and its associated members 208 prevent a "playful" individual from moving the carriers 110 against their springs 78 to back up the loaded buckets 111 after some buckets 111 have dispensed the contained product. Referring to Fig. 9, attempted counter-clockwise movement of the carriers 110 with the upper section 32 locked is prevented by engagement of the respective member 208 in the notch 83 of the respective sprocket 79. Clockwise dispensing movement of the carriers 110 is permitted, for the members 208 ride freely over the sprockets 79. When the upper section 32 is raised for refilling the carriers 110, the wire 211 is raised which pivots the member 205 to simultaneously pivot all of the members 208 out of engagement with the sprockets 79, since they are adjacent the side 207. The carriers 110 are then free for refill movement.

It is to be noted that the various elements of the machine 30 are pivotally or rotatably related. Friction is thereby reduced to a minimum, which is essential in the present machine 30, since the total actuating movement of a button 43 is less than about an inch. The instant machine 30 reduces the work required by a user to the mere moving inwardly of a button a short distance and the subsequent release thereof.

The special features of the present machine 30 are apparent, but particular note should be taken of the fact that none of the various elements of the machine 30 is required to move through a relatively great distance or is required to make a strenuous effort in the performance of its particular duty. There are no parts which can readily become inoperative through use, obviating the abuse to which dispensing machines are often subjected due to faulty operation occasioned by failure of the internal mechanism. The action of the present machine is both positive and fast. The movement of a particular carrier 110 can be observed by the purchaser so that the purchaser can immediately perceive whether or not the machine is functioning, thereby doing away with the suspense and subsequent irritation too often occasioned by dispensing machines now being used.

The present machine 30 is vermin-proof, inasmuch as the guide shield 123 cooperates with the support plates 50 and 51, the strip 34, and the top section 32 to completely enclose the carriers 110. The particular buckets 111 disposed adjacent the openings 44 are, of course, open to the exterior, but these buckets are empty. The upper portion 32 of the cover 31 is constructed so that the buckets 111 adjacent the openings 44 are substantially in closing relation. It is apparent that some additional closing medium may be employed to further insure the closing off from the exterior of those buckets not opening into the openings 44. The machine 30 can, therefore, be employed to dispense chocolate bars, and the like, without the danger of becoming infested with vermin, and the like.

From the foregoing it is clear that the dispensing operation of the machine 30 is simple. Further, it is as obvious that the loading of the machine is also quite simple. The capacity of the machine 30 is large, inasmuch as the carriers 110 are continuous. The products within the buckets 111 of the carriers 110 are individually supported by the buckets 111, thereby ob-

vilating crushing of the products being dispensed, which often happens where chocolate bars, cigarettes, and the like, are stacked, one upon the other. This failure particularly occurs as regards stacked chocolate bars, and the like, in warm weather.

It is apparent that the machine 38 shown and described fulfills all of the objects and advantages sought therefor. It is to be understood that the foregoing description and accompanying drawings have been given by way of illustration and example, and not for purposes of limitation, the invention being limited only by the claims which follow.

What is claimed is:

1. A dispensing machine comprising supporting means, a plurality of endless carriers supported thereby, each carrier including a plurality of buckets pivotally connected to form an endless chain, means for automatically moving each carrier, means normally locking said carriers against dispensing movement, and means for releasing an individual carrier to permit said moving means to move the carrier a predetermined amount.

2. A dispensing machine comprising a support, a plurality of carriers movably supported by said support, each carrier comprising a plurality of buckets pivotally connected to form an endless bucket chain, individual means for moving each carrier, individual means releasably connected to each carrier for preventing movement thereof by said moving means, individual means for releasing each movement-preventing means, and means normally preventing operation of said individual release means.

3. A dispensing machine comprising a support, a plurality of carriers movably supported by said support, individual means for moving each carrier, individual means releasably connected to each carrier for preventing movement thereof by said moving means, individual means for releasing each movement-preventing means, individual means for limiting the movement of each carrier upon the restraint of said release means in release position, and means normally preventing operation of said individual release means.

4. A dispensing machine comprising a support, a plurality of carriers movably supported by said support, individual means for moving each carrier, individual means releasably connected to each carrier for preventing movement thereof, individual means for releasing each movement-preventing means, individual means for limiting the movement of each carrier upon the restraint of said release means in release position, means for preventing the operation of more than one release means at a time, means normally preventing operation of said individual means, means preventing back-up movement of the carriers when the machine is in service, and means for governing the speed of movement of the carriers upon being released.

5. In a dispensing machine, a bucket adapted to receive a product, said bucket including opposed side walls, a portion of each side wall being offset relative to the other portion of the wall, each of the greater spaced portion of the side walls including an aperture and each of the lesser spaced portions including a stud, and diverging top and bottom walls.

6. In a device of the kind described, a carrier, a movable support for said carrier including a plurality of stop elements movable therewith, means for moving said carrier, means engaging

5 a stop element to prevent movement of said carrier, means to release said stop-engaging means from said stop, and means for preventing rotation of said carrier upon release of the engaged stop beyond a predetermined degree to insure periodical stopping of said carrier.

7. A dispensing machine comprising a case, a support within said case, a first shaft immovably supported by said support, a second shaft rotatably journaled in said support below said first shaft, a plurality of double sprockets freely rotatable on each shaft, a bucket chain carrier supported on each opposed pair of sprockets, a heavy coil spring connected between each upper double sprocket and the fixed shaft tending at all times to rotate the sprocket and its associated carrier in one direction, a third shaft journaled in said support just below said upper sprockets, a pair of bell crank levers fixed to each other and freely rotatable on said third shaft adjacent each upper sprocket, a link pivoted to each pair of bell cranks and fixed to a button mounted in the case for reciprocal movement, spaced stops on each upper sprocket adjacent the periphery, an extension on one of the bell cranks of each pair disposed to normally engage a stop on the associated sprocket, a flange formed as part of the other of the bell cranks of each pair adapted to be contacted by the stop following the engaged stop under circumstances of release, a bar connected to said third shaft by arms fixed to said third shaft, said bar extending along adjacent the bell cranks and being adapted to be contacted and moved by a pivoted pair of bell cranks to pivot the third shaft, means preventing the pivotal movement of more than one pair of bell cranks at a time, means normally preventing operation of the buttons, a locking mechanism to prevent back-up movement of the carriers when the machine is in use, and a governor connected to said lower rotatable shaft adapted to control individually the movement of each carrier effected by its associated spring.

45 8. A dispensing machine comprising supporting means, spaced sprockets supported thereby, an endless carrier disposed about said sprockets including a plurality of buckets for dispensing articles, means for automatically moving said carrier in one direction, means normally preventing automatic rotation of said carrier, means for releasing said rotation preventing means, and means normally preventing operation of said releasing means, said rotation preventing means including a plurality of spaced stops on one of the sprockets and a pivotally mounted lever having means engaging a stop.

9. A dispensing machine comprising supporting means, spaced sprockets supported thereby, 60 an endless carrier disposed about said sprockets including a plurality of buckets for dispensing articles, means for automatically moving said carrier in one direction, means normally preventing automatic rotation of said carrier, means for releasing said rotation preventing means, means for limiting the movement of the carrier upon the restraint of said release means, and means normally preventing operation of said releasing means, said rotation preventing means including a plurality of spaced stops on one of the sprockets and a pivotally mounted lever having means engaging a stop, said limiting means including a second lever pivotally mounted to move with the first lever having means adapted to be engaged by the stop just released by the

engaging means of the first lever upon the restraint of the release means.

10. A dispensing machine comprising a casing, an article dispensing opening in said casing, a carrier movably supported in said casing, said carrier being located relative to said opening to store the greater part of articles to be dispensed below the said opening, means for moving said carrier, means releasably connected to

said carrier for preventing movement thereof by said moving means, means for releasing said movement-preventing means, means for limiting the movement of said carrier upon the restraint of said release means in release position, and means normally preventing operation of said release means.
